UNITED STATES PATENT OFFICE.

WILLIAM IRVIN EVERSON, OF BRILLIANT, OHIO.

DESIGN FOR A HOOK FOR WAISTBAND-FASTENINGS.

SPECIFICATION forming part of Design No. 30,950, dated June 6, 1899.

Application filed April 22, 1899. Serial No. 714,110. Term of patent 7 years.

To all whom it may concern:

Be it known that I, WILLIAM IRVIN EVERSON, a citizen of the United States, residing at Brilliant, in the county of Jefferson and State of Ohio, have invented and produced a new and useful Design for a Hook for Waistband-Fastenings, of which the following is a specification, reference being had to the drawings, in which—

10 Figure 1 is a top plan view of my invention, and Fig. 2 is a longitudinal sectional view.

My design consists, essentially, of a flat plate A, wedge shape and rounded at one end, as shown at A', while the opposite end is shaped to form ears A², having apertures

A³. The rounded end A' is also provided with an aperture A⁴.

B is a tongue portion integral with the plate and bent back at B' and resting parallel with the face of the plate, said tongue having a depression B².

Having thus fully described my invention, what I claim as new, and desire to secure by Letters Patent of the United States, is—

25 The design for a hook for waistband-fastenings substantially as herein shown and described.

WILLIAM IRVIN EVERSON.
